[57] CLAIM

The ornamental design for a sliding organizer rack, as shown and described.

DESCRIPTION

FIG. 1 is a bottom, front, and left side perspective view of a sliding organizer rack showing our new design, the partial broken-line depiction of a shelf being for illustrative purposes only and forming no part of the claimed design;

FIG. 2 is a bottom plan view thereof;

FIG. 3 is a right side elevational view thereof;

FIG. 4 is a front end elevational view thereof;

FIG. 5 is a top plan view thereof;

FIG. 6 is a right side elevational view thereof; and

FIG. 7 is a rear end elevational view thereof.
The rack is shown in its partially extended position in FIG. 1, but fully retracted in the remaining figures.
